CLAIM

I claim the ornamental design for a closure, as shown and described.

DESCRIPTION

FIG. 1 is a perspective view of a closure in accordance with one embodiment of the design.

FIG. 2 is a top plan view of the closure in FIG. 1, the bottom of the closure forming no part of the claimed design.

FIG. 3 is a side elevational view of the closure taken from the right side in FIG. 2, the side elevational views from the top, left and bottom of FIG. 2 being identical to FIG. 3.

FIG. 4 is a perspective view of a closure in accordance with another embodiment of the design, the recessed design being shown in phantom for environment.

FIG. 5 is a top plan view of the closure in FIG. 4, the bottom of the closure forming no part of the claimed design; and, FIG. 6 is a side elevational view taken from the right in FIG. 5, the side elevational views taken from the top, left and bottom of FIG. 5 being identical to FIG. 6.
